CRIBBING

Otto S. Flath, Chicago, Ill.

Application September 28, 1942, Serial No. 460,023

2 Claims. (Cl. 61—47)

My invention relates to cribbing composed of metal or steel members for constructing walls for supporting embankments or "fills," being especially adapted for use in the construction of walls for trenches and the like where time is of the essence and convenience or ease in handling is essential.

The invention has for its object the provision of easily fabricated members of comparatively simple construction, which may be readily assembled into the desired wall and the assembled members secured together without need for special skill to provide a sturdy retaining wall.

Another object of the invention is the provision of an economical wall composed of a few standard elements involving a unit or member of sheet steel—which may be pressed into shape—which may be employed either as a header or as a stretcher and the ends of the header members and of the stretcher members formed to provide interengaging relation and to be rigidly secured together; with the members preferably being provided with rigidifying surfaces so arranged or formed that the respective members may be assembled into contiguous relation so as to provide an uninterrupted outer face whereby the fill is prevented from filtering therethrough.

Another object of the invention consists in forming a member or unit adapted for use either as a header or as a stretcher and hence requiring a single former or die to be employed in fabricating the respective units, which therefore materially reduces the cost of manufacture.

The above-enumerated objects and advantages as well as other advantages inherent in the invention will all be readily comprehended from the following detailed description of the accompanying drawings wherein:

Figure 1 is a perspective view of one of the units of my improved cribbing with an intermediate portion broken away.

Figure 2 is a perspective view of a section of cribbing illustrating the contiguous ends of a number of units assembled to constitute headers and stretchers, with portions broken away.

Figure 3 is a plan view of a portion of cribbing assembly.

Figure 4 is a side elevation of cribbing assembly with an intermediate portion broken away.

Figure 5 is a view similar to Figure 2 showing a modified form of assembly.

Figure 6 is a perspective view of a portion of cribbing as viewed from the interior and showing a modified form.

Figure 7 is a similar view showing another modification.

Figure 8 is plan view of the header unit shown in Figure 7, with an intermediate portion broken away.

In the exemplification of the invention disclosed in Figures 1 to 4, the cribbing involves a plurality of uniform units or members arranged at their ends in overlapping engagement, with the overlapping ends secured together by suitable fastening means. That is to say, the headers 15 and the stretchers 16 of the cribbing shown in Figures 2 and 3 are of similar construction and consist of a single steel sheet 17 of predetermined width and length, as shown in Figure 1, whose ends 18, 18 are bent at right angles to the body portion and preferably toward the same side of the sheet and the body portions 17, preferably provided with longitudinally extending corrugations or formed with laterally bowed and longitudinally extending rigidifying surfaces as at 19 which terminate a short distance from the angularly disposed ends 18, 18; while the marginal portions above and below the bowed portions 19 are flat and are disposed in the same plane with each other.

I prefer to provide the bowed portion, at predetermined distances apart, with bolt receiving holes as at 20 which preferably are arranged at the longitudinal median line of the member 17, in order that a pair of the members may be arranged in flush parallel relation and bolted together at 21 to provide a rigid two-piece unit or header 15 with the rigidifying portions 19 of the united members disposed laterally outward on both sides of the cribbing, see Figure 3, and adapted to withstand the lateral strains and pressures of the "fill." The member 17, adjacent the ends and preferably beyond the ends of the bowed portion 19, is also provided with bolt-holes 22 arranged one above the other; while the bent ends 18 also are provided with bolt-holes 23, as clearly shown in Figure 1.

Each course of headers 15 consists of a pair of members 17 bolted together by bolts 21 as shown in Figure 2, with the bent ends 18 of the two members disposed in opposite directions and arranged in overlapping relation with the outer faces of the adjacent ends of the stretchers 16; the longitudinal edges of the superposed headers, in Figure 2, being arranged in abutting relation with each other.

In the cribbing construction shown in Figure 2, the stretchers 16 (of construction similar to the member 17 shown in Figure 1) are arranged in

staggered or offset relation with the respective courses of headers so that each stretcher 16 will be in overlapping relation with a pair of superposed headers. The ends of the stretchers are arranged rearward of the bent ends 18 of the two superposed headers 15 so as to extend substantially half way, vertically, of each header, with the bent ends 18 of the stretcher extending flush with the plain surface of the header having bolt-holes 22. The ends 18 of the stretchers are then secured to the headers by bolts 24—one bolt extending through the lower hole 22 of the upper header and the other bolt 24 extending through the upper hole 22 of the lower header—the bolts 24 being disposed through the adjacent ends 18 of the two stretchers 16 and through the two pieced header unit 15. The ends 18 of the headers 15 are secured to the stretcher members 16 located on opposite sides of the header unit 15 by bolts 25 which pass through the holes 23 in the ends 18 of the header units and through the registering holes 22 of the stretchers. With this arrangement, the headers and stretchers are arranged in interengaging and joint reenforcing relation, with a single bolt securing two stretchers to a header unit, and the bolts relieved of the strains that would result from the outward thrust of the back-fill.

As the right angularly bent ends 18 of the header overlap the outer sides of the stretchers whose ends 18 are bolted to the header unit by bolts 24, the stretchers are held against the outward pressure of the "fill" and bolts 25 may, if desired, be omitted.

It will be understood that the stretchers of one course are arranged in edge-to-edge contact with the stretchers of the adjacent courses thereby providing the cribbing with a continuous outer face and filtering of the "fill" therethrough prevented.

With the stretchers 16 arranged in staggered relation, namely overlapping the ends of two headers as shown in Figure 2, a sturdy structure is provided wherein the respective courses of headers and stretchers are secured to each other and the possibility of one course shifting on the other is made impossible; and outward movement of the cribbing is also made impossible by the "fill" located in the rectangular pockets or chambers between the parallelly arranged and rearwardly disposed courses of headers 15 united at both ends by the inner and the outer courses of stretchers 16, as shown in Figure 3.

The cribbing, as is the usual practice, is preferably provided with a suitable foundation, as for example shown at F in Figure 4, and the cribbing may be of any suitable or desired height in keeping with the particular conditions encountered and the length of the headers adjacent the top of the cribbing may be reduced if desired—the shorter headers, however, being of the same construction as shown in the drawings.

In Figure 5 I show a portion of cribbing composed of the headers and stretchers similar to the member shown in Figure 1, with the headers and stretchers arranged and bolted together in the manner shown in Figure 2.

The structure shown in Figure 5 differs from that of Figure 2 by providing a pair of angle bars 26 which extend from top to bottom of the cribbing and, in conjunction with the attached ends of the headers and stretchers, form a vertically disposed beam whereby the cribbing is greatly reenforced. The angle bars 26 are arranged with one side of each bar 26 disposed be-

tween the two parallelly arranged members of the header unit 15, while the other side of each bar 26 is arranged to the cribbing exterior in overlapping relation with the bent ends of the headers 15. The angle bars are provided with bolt-holes adapted to register with the bolt-holes 23 in the flanges of the stretchers 16 and with the bolt-holes 22 in the header members so that a single bolt 24 may be employed for securing the header unit 15, the stretchers 16, on opposite sides of the header unit, and the two angle bars 26 together. In order to further tie the respective courses together I also prefer to provide the exposed sides of the angle bars 26 with bolt-holes 27 arranged to register with the bolt-holes 22 in the stretchers 16 and adapted to receive the bolt 28.

As stated, the angle bars 26 extend from top to bottom and the lower ends of the bars may extend a distance beneath the bottom courses of headers and stretchers to permit the extended ends to be embedded in the ground or cribbing foundation.

In Figure 6 I show a modified form of cribbing especially in so far as the stretchers are concerned. The headers 15 are of the preshaped construction shown in Figure 1 and the headers composed of single members as shown; or each unit may consist of two members arranged in face-to-face relation to provide the header section or unit disclosed in Figure 2, with the flanges or ends 18 of the two members extending in opposite directions and in overlapping relation with the outer faces of the stretchers disposed on opposite sides of the header unit 15. By reason of the type of stretcher employed, the header members of Figure 6 need not be provided with the bolt-holes 22 shown in Figure 1; the flanges or ends 18, however, preferably being provided with the pair of bolt-holes 23 as in Figure 1. The stretchers 30, which may be of the same length as the headers or of any desired length, are of channel form with the longitudinal sides or flanges 31 disposed inwardly so that the base portions of the channel stretchers may extend in flush relation or contact with the flanges or ends 18 of the headers as shown; and the base portions of the channel members adjacent their ends are provided with a pair of bolt receiving holes adapted to register with the holes 23 in the flanges or ends of the headers to receive the bolts 32.

The stretchers 30 are also shown in staggered relation with the headers; that is to say, one course of stretchers is arranged in lapping relation with two adjacent courses of headers (as in Figure 2) so that each stretcher at each end is secured to two superposed headers thereby firmly securing the respective courses together. The stretchers 30, at spaced intervals apart in their sides or flanges 31, are provided with bolt-holes 33 to receive bolts 34 whereby the adjacent courses of stretchers are secured together.

Figure 7 discloses another modification of cribbing wherein the headers 35 consist of preformed steel sheets preferably provided intermediate their ends with the dished portion or longitudinally extending reenforcing corrugations 19, similar to that shown in Figure 1; while the ends of the headers, instead of being flanged or bent laterally as in Figure 1, are provided with a number of transversely or vertically disposed corrugations 36, and the portions adjacent these corrugations provided with the pair of bolt-holes 22 shown in Figure 1.

The stretchers 37 consist of elongated sheets

of steel preferably provided with a plurality of longitudinally disposed corrugations 38 which terminate a distance away from the ends as shown in Figure 7 to provide the plane portions which are bent laterally or at right angles as shown at 39. These bent ends or flanges are provided with transversely or vertically disposed corrugations 40 formed to match the corrugations 36 of the headers and are arranged in mating relation therewith. The corrugated ends or flanges 39 are also provided with a pair of vertically spaced bolt-holes 41 to receive bolts 42 which extend through the registering holes 41 of the flanges 39 of the stretchers on opposite sides of the headers 35 and through the bolt-holes 22 in the headers, which firmly hold the corrugations of the headers and stretchers in interlocking relation. The stretchers 31 preferably are also arranged in overlapping relation with two superposed headers, thereby securing the respective courses together; the interlocking corrugations relieving the bolts of pulling strains. In the modified form of cribbing shown in Figure 7, each header unit may consist of a single sheet or member whose general configuration is clearly shown in Figure 8.

It will be understood that the headers and stretchers are, respectively, constructed in the same manner at both ends, with the inner ends of the headers and stretchers arranged in the same manner as at the forward or outer ends.

The exemplifications shown and described are believed to be the best embodiments of my invention, but certain modifications are possible without, however, departing from the spirit of my invention as defined in the appended claims.

What I claim is:

1. A cribbing composed of similarly formed elongated rectangular metal sheets with their ends uniformly bent at right angles toward the same sides of the sheets, the sheets adjacent the ends and said angularly disposed ends being provided with uniformly spaced bolt-holes, the sheets being provided with straight longitudinal marginal portions and arranged in superposed relation with the longitudinal edges of the sheets of one course resting on the longitudinal edges of the sheets in the subjacent course, certain courses of superposed sheets constituting headers while other

courses are arranged at right angles to the first mentioned courses and at opposite sides of the longitudinal axis of the first mentioned courses to constitute stretchers, with the stretcher sheets arranged in staggered relation with the sheets of the headers, the ends of the stretcher sheets being arranged against the rear faces of the angular ends of the header sheets while the angularly bent ends of the stretcher sheets are disposed inwardly in overlapping relation with the header sheets; and bolts disposed through the angular ends of the header sheets and the stretcher sheets and through the angularly bent ends of the stretcher sheets and the header sheets.

- 5 2. A cribbing composed of a plurality of uniform elongated metal sheets whose ends are bent laterally toward the same sides of the sheets, the sheets adjacent the bent ends and the bent ends being provided with uniformly spaced fastening means receiving openings, certain of said sheets being arranged edgewise on each other to constitute courses of headers said courses consisting of a pair of sheets arranged in back-to-back relation with the bent ends of the two sheets disposed outwardly in opposite directions, while other sheets are arranged edgewise on each other to constitute courses of stretchers disposed at right angles to the header courses and on opposite sides of the longitudinal axis of the header courses, the bent ends of the stretchers being disposed inwardly in overlapping relation with the header sheets while the bent ends of the headers are arranged on the outer faces of the stretcher sheets; a pair of vertically disposed angle bars arranged 30 in side-to-side relation between the ends of the pair of header sheets with the other side of each bar arranged in overlapping relation with the bent ends of the respective header sheets, one side of said angle bars having openings registering with the holes in the bent ends of the stretcher sheets and the body of the header sheets while the other side of the angle bars has openings registering with the openings in the bent ends of the header sheets and in the stretcher sheets; and means disposed through the registering openings of the respective units and angle bars for securing all of said elements together.
- 10 3. A cribbing composed of a plurality of uniform elongated metal sheets whose ends are bent laterally toward the same sides of the sheets, the sheets adjacent the bent ends and the bent ends being provided with uniformly spaced fastening means receiving openings, certain of said sheets being arranged edgewise on each other to constitute courses of headers said courses consisting of a pair of sheets arranged in back-to-back relation with the bent ends of the two sheets disposed outwardly in opposite directions, while other sheets are arranged edgewise on each other to constitute courses of stretchers disposed at right angles to the header courses and on opposite sides of the longitudinal axis of the header courses, the bent ends of the stretchers being disposed inwardly in overlapping relation with the header sheets while the bent ends of the headers are arranged on the outer faces of the stretcher sheets; a pair of vertically disposed angle bars arranged 35 in side-to-side relation between the ends of the pair of header sheets with the other side of each bar arranged in overlapping relation with the bent ends of the respective header sheets, one side of said angle bars having openings registering with the holes in the bent ends of the stretcher sheets and the body of the header sheets while the other side of the angle bars has openings registering with the openings in the bent ends of the header sheets and in the stretcher sheets; and means disposed through the registering openings of the respective units and angle bars for securing all of said elements together.
- 20 4. A cribbing composed of a plurality of uniform elongated metal sheets whose ends are bent laterally toward the same sides of the sheets, the sheets adjacent the bent ends and the bent ends being provided with uniformly spaced fastening means receiving openings, certain of said sheets being arranged edgewise on each other to constitute courses of headers said courses consisting of a pair of sheets arranged in back-to-back relation with the bent ends of the two sheets disposed outwardly in opposite directions, while other sheets are arranged edgewise on each other to constitute courses of stretchers disposed at right angles to the header courses and on opposite sides of the longitudinal axis of the header courses, the bent ends of the stretchers being disposed inwardly in overlapping relation with the header sheets while the bent ends of the headers are arranged on the outer faces of the stretcher sheets; a pair of vertically disposed angle bars arranged 40 in side-to-side relation between the ends of the pair of header sheets with the other side of each bar arranged in overlapping relation with the bent ends of the respective header sheets, one side of said angle bars having openings registering with the holes in the bent ends of the stretcher sheets and the body of the header sheets while the other side of the angle bars has openings registering with the openings in the bent ends of the header sheets and in the stretcher sheets; and means disposed through the registering openings of the respective units and angle bars for securing all of said elements together.
- 25 5. A cribbing composed of a plurality of uniform elongated metal sheets whose ends are bent laterally toward the same sides of the sheets, the sheets adjacent the bent ends and the bent ends being provided with uniformly spaced fastening means receiving openings, certain of said sheets being arranged edgewise on each other to constitute courses of headers said courses consisting of a pair of sheets arranged in back-to-back relation with the bent ends of the two sheets disposed outwardly in opposite directions, while other sheets are arranged edgewise on each other to constitute courses of stretchers disposed at right angles to the header courses and on opposite sides of the longitudinal axis of the header courses, the bent ends of the stretchers being disposed inwardly in overlapping relation with the header sheets while the bent ends of the headers are arranged on the outer faces of the stretcher sheets; a pair of vertically disposed angle bars arranged 45 in side-to-side relation between the ends of the pair of header sheets with the other side of each bar arranged in overlapping relation with the bent ends of the respective header sheets, one side of said angle bars having openings registering with the holes in the bent ends of the stretcher sheets and the body of the header sheets while the other side of the angle bars has openings registering with the openings in the bent ends of the header sheets and in the stretcher sheets; and means disposed through the registering openings of the respective units and angle bars for securing all of said elements together.

OTTO S. FLATH.
